CLAIM

The ornamental design for a cable management unit, as shown and described.

DESCRIPTION

FIG. 1 is a front perspective view of a cable management unit according to the present invention.

FIG. 2 is a back perspective view of the cable management unit FIG. 1.

FIG. 3 is a front view of the cable management unit of FIG. 1.

FIG. 4 is a back view of the cable management unit of FIG. 1.

FIG. 5 is a left side view of the cable management unit of FIG. 1.

FIG. 6 is a right side view of the cable management unit of FIG. 1.

FIG. 7 is a top view of the cable management unit of FIG. 1; and,

FIG. 8 is a bottom view of the cable management unit of FIG. 1.

The broken lines in FIGS. 1-8 are included for the purpose of illustrating environmental structure and form no part of the claimed design.

1 Claim, 8 Drawing Sheets
